UNITED STATES PATENT OFFICE.

HENRY PHILLIP KRAFT, OF RIDGEWOOD, NEW JERSEY.

PUMP COUPLING.

Application filed August 5, 1921. Serial No. 490,175.

To all whom it may concern:

Be it known that I, HENRY PHILLIP KRAFT, a citizen of the United States of America, residing in Ridgewood, in the county of Bergen and State of New Jersey, have invented certain new and useful Improvements in Pump Couplings, of which the following is a specification.

The present invention relates to pump 10 couplings and aims to provide certain useful improvements therein.

The present invention is particularly directed to that type of pump coupling whereby a quick attachment and detachment of 15 said coupling with a tire valve or the like may be readily made, and one wherein notwithstanding its comparative simple construction, provides a very secure union between the coupled parts. A pump coupling 20 of such construction is disclosed in my earlier filed application Serial No. 471,274, filed May 20, 1921.

According to the present invention a pump coupling of the same general character as that disclosed in my earlier filed application is provided, the important features 25 of improvement being in the manner of construction and the materials used. Where, in the earlier filed construction the body portion 30 of the coupling is preferably made from brass stock of appropriate cross section by subjecting it to the necessary cutting, drawing and forming operations, the body portion of the device according to the present 35 invention is preferably formed of aluminum by the die casting process. The wear resisting qualities of aluminum however being not as good as those of brass, the parts of the pump coupling which are subjected to greatest 40 wear are preferably made from hard brass or other hard non-oxidizable metal.

Broadly speaking the invention may be said to consist of a pump coupling formed of aluminum having an enlarged bore adapted 45 to fit over a valve nipple or other threaded member and a manually operable dog adapted to be moved into said bore to engage the valve nipple to hold the coupling thereon. The inner wall of the bore and the 50 movable dog being the parts of the coupling which are subjected to wear, they are preferably formed of a harder non-oxidizable metal. Accordingly, it is an object of the present invention to provide a pump coupling 55 of light weight which can be easily and cheaply made without detracting from

its utility. The invention also includes other features of improvement which will be hereinafter more fully set forth.

Referring to the drawings which show 60 two embodiments of the invention:

Figure 1 is a longitudinal section, showing the coupling in engagement with a valve nipple;

Figure 2 is a section taken on the line 2—2 65 of Figure 1;

Figure 3 is a transverse section of Figure 1 taken on the line 3—3;

Figure 4 is a longitudinal section, showing a modification. 70

Referring to the drawings, let A indicate the coupling as a whole, which consists of a body portion B and the usual shank C for engagement with a rubber hose. The body portion B is preferably enlarged and formed 75 with a bore D which is adapted to pass over the end of a valve nipple, the wall of the bore D being preferably unthreaded so as to slip easily over said valve nipple. The body portion is recessed at E to receive a 80 movable dog or catch member F, said dog being provided with screw threads at its inner end and adapted to be moved into the bore D to engage the valve nipple and to be retracted therefrom to disengage said nipple. 85

The dog is formed with flat sides which act to guide the dog and maintain the screw threads thereon in proper alignment with respect to the valve nipple. The head of the dog is enlarged as indicated by the letter f 90 (Fig. 1), said enlarged head serving as a stop, limiting the inward movement of the dog and also as a bearing surface for an operating cam G by means of which the dog is moved inwardly. The operating cam G 95 is in the form of a quadrant of a circle the inner end of which is rounded and pivotally mounted off center on a pin I supported by a pair of ears b integrally formed on the body portion. The manipulating edge of 100 the operating cam is herein shown as roughened or milled to provide a good gripping surface for the finger. The foregoing description substantially describes an embodiment of my invention disclosed in my earlier filed application hereinbefore mentioned, and is not broadly claimed herein. 105

According to the present invention, substantially the same mechanical operation of the device is maintained, but the construction is such that the device is much lighter and can be more easily and cheaply made. 110

This I accomplish by die casting the body portion, shank and ears from some easily castable metal, preferably aluminum. However, as cast aluminum is comparatively soft and has not the wear resisting qualities and hardness essential to screw thread clamping elements, the screw thread engaging surfaces of the coupling are hence made from some hard metal. It is also essential that this hard metal be substantially non-oxidizable, otherwise the utility of the device will be greatly impaired. As seen in the drawings, the parts of the pump coupling of the type disclosed which are subjected to the greatest wear are the bore D of the body portion B, the dog E and the pin I. These parts are accordingly made of brass or other suitable hard non-oxidizable material. In order to provide the bore of the body portion with a suitable lining of wear resisting material, said bore during the casting operation is formed with a portion of larger diameter indicated at K. Into this enlarged bore K is forced a hard brass bushing L which is provided with a suitable recess to accommodate the dog F. The bushing also acts to retain a sealing gasket M within the coupling. The gasket M may be of any desired construction and is herein shown as a plunger, formed with a conical bore m in the base of the said bore facing the shank C whereby a greater surface is exposed to the incoming pressure, thus insuring a more perfect seal between the coupling and the end of the tire valve.

The device disclosed in Figure 4 only differs from that shown in Figures 1-3 in that the coupling is formed with the hose shank at an angle to the body portion instead of, in alignment therewith.

In operation, to apply the device the operating cam or finger piece is positioned so that the dog lies either in its retracted position shown in Figure 4, or so that it may be readily moved into said position upon contacting the valve nipple. In this position the coupling is slipped over the valve nipple and the finger piece tilted or rotated downwardly

to bring the threaded dog into engagement with the nipple, as shown in Figure 1. A very secure connection is thus provided. When it is desired to remove the coupling a tilting or rotation of the finger piece in the opposite direction and the lifting off of the coupling is all that is necessary.

While I have shown two embodiments of the invention as applied to a pump coupling it is obvious that the inventive thought involved may be applied to other devices such as dust caps etc. and I do not wish to be limited to the particular construction illustrated since various modifications may be resorted to without departing from the spirit of the invention.

What I claim is:—

1. A pump coupling or the like comprising a shank, a body portion having a recess therein, a dog movable in said recess, and a sleeve within the body portion, said body portion being formed of easily castable metal and the dog and sleeve being formed of non-oxidizable wear resisting metal.

2. A pump coupling or the like, comprising a body portion having an enlarged bore therein, a dog movable in said bore and adapted to engage a valve nipple or the like to hold the coupling thereon and a sleeve in said bore through which said dog is movable.

3. A pump coupling or the like, comprising a recessed body portion having an enlarged bore therein, a dog movable in said bore and adapted to engage a valve nipple or the like to hold the coupling thereon and a recessed sleeve in said bore through which said dog is movable, the recesses in the body portion and sleeve substantially coinciding.

4. A pump coupling or the like, comprising a body portion having two bores, the larger being in advance of the smaller, a plunger gasket in the smaller bore, a sleeve in the larger bore holding said gasket in operative position and a dog movable in the bore of larger diameter through said sleeve.

In witness whereof, I have hereunto signed my name.

HENRY PHILLIP KRAFT.
